UNITED STATES PATENT OFFICE.

FREDERICK B. GOULD, OF FARMER CITY, ILLINOIS.

SLIDE-BAND FOR COLLARS.

No. 892,989.

Specification of Letters Patent.

Patented July 14, 1908.

Application filed December 21, 1906. Serial No. 348,846.

To all whom it may concern:

Be it known that I, FREDERICK B. GOULD, citizen of the United States, residing at Farmer City, in the county of De Witt and State 5 of Illinois, have invented certain new and useful Improvements in Slide-Bands for Collars, of which the following is a specification.

This invention relates to a device adapted to be attached to a shirt collar of the "turn-down" variety and to form a slide-way for 10 the neck-tie embracing the collar.

The especial object of my invention is to provide a device that can be readily attached to and detached from the ordinary turn-down collar, whereby a smooth sliding surface is provided for the neck-tie, and whereby the inner and outer bands of the collar will be held apart so that they cannot pinch the neck-tie band when the latter is moved longitudinally 15 in the adjustment of the ordinary tie of "four-in-hand" style.

A further object of my invention is to provide a device that is adjustable to various sizes of collars and which will conform regularly 20 to irregularities in the neck opening of the shirts on which such collars are commonly used.

A further object is to provide a device of this character that can be cheaply manufactured and quickly and easily attached to and detached from the ordinary linen collar.

Referring to the accompanying drawings which form a part of this application:—Figures 1 and 2 are views of opposite sides of the 25 invention which forms the subject matter of my invention, in its preferred form; Figs. 3 and 4 are similar views showing a slightly modified form of said invention; Fig. 5 is a cross-section of the device shown in Figs. 40 1 and 2; Fig. 6 is a cross-section of the form of my invention shown in Fig. 3, and Fig. 7 is a view showing the application of my invention to a collar, portions of the latter being broken away to more clearly disclose the 45 construction and application of my device.

Referring to the accompanying drawings in detail, 8 represents a strip or band of thin material having smooth surfaces, and preferably celluloid, though other material of a 50 similar character may be used. These strips are preferably cut in the form shown, and midway their ends are cut away as shown at 9, to afford access to the button hole at the back of the ordinary collar. Secured to one

side of the strip by suitable rivets 11 are 55 small loops 10 between which and the band 8, are slidably mounted the hooks 12 shown in Fig. 1, which are formed of thin metal and consist of a hook 14 at their lower end, and a shoulder 13 at their upper end. The 60 shank of this hook device slides freely under the loop 10, but is prevented from becoming detached by the hook 14 at its lower end and the shoulder 13 at the upper end. On the opposite side of the strip, the upper 65 and lower edges are turned over at different points to form flanges 15 which project outwardly at an acute angle from the strip and form spacing members between which the neck-tie may freely slide, and they also 70 prevent the outer and inner bands of the collar from laying closely together so as to bind on the neck-tie. The upper flanges 15, 15^a, prevent the neck-tie bands from sliding above the strip and the lower flanges prevent 75 the neck tie band from falling below the strip.

In the modified form of my device shown in Figs. 3, 4, and 6, instead of providing the hooks 12, I form hooks 16 integrally 80 with the strips, and with the exception of being non-adjustable these hooks serve the same purpose as those above described, and of course a device so made is cheaper to manufacture than the form of device shown 85 in Figs. 1, 2, and 5.

In applying my device I place it between the inner and outer bands of the collar with the hooks 14 or 16 extending inwardly toward the neck of the wearer, and engaging 90 the lower edge of the inner band. The neck-tie is then placed between the device and the outer band of the collar and the latter is buttoned to the shirt in the usual manner, thus entirely covering the slide-band. Owing to 95 the nature of the material of which the strip or slide-band is made, and the space left between the slide band and the collar, the neck-tie can be readily moved endwise, thus facilitating the operation of properly adjusting 100 the same.

It will be apparent that various modifications may be made in details of this device without altering its functions and without involving more than mechanical skill.

What I claim is:—

1. As a new article of manufacture, a slide-band for collars, consisting of a strip of suit-

able material having overhanging flanges, and means for detachably securing said strip to the band of a collar.

2. As a new article of manufacture, a slide-
5 band for collars, consisting of a strip of suitable
material having overhanging flanges,
and adjustable means for detachably securing
said strip to the band of a collar.

3. As a new article of manufacture, a slide-
10 band for collars, consisting of a strip of cel-

luloid having integral projecting flanges
formed thereon, and means for detachably
securing said strip to the band of a collar.

In testimony whereof I affix my signature
in presence of two witnesses.

FREDERICK B. GOULD.
